J. K. BRYANT

SELF GRIPPING ADJUSTABLE COUPLING

Filed Oct. 22, 1924

Inventor:
Julian K. Bryant
by M. Harrison
Attorney.

UNITED STATES PATENT OFFICE.

JULIAN K. BRYANT, OF LOWELL, MASSACHUSETTS, ASSIGNOR TO SECURITY ENGINEERS, INCORPORATED, OF LOWELL, MASSACHUSETTS, A CORPORATION OF MASSACHUSETTS.

SELF-GRIPPING ADJUSTABLE COUPLING.

Application filed October 22, 1924. Serial No. 745,262.

To all whom it may concern:

Be it known that I, JULIAN K. BRYANT, a citizen of the United States, and resident of Lowell, in the county of Middlesex and 5 State of Massachusetts, have invented certain new and useful Improvements in Self-Gripping Adjustable Couplings, of which the following is a specification.

This invention relates to mechanisms or 10 devices in which a screw is employed for purposes of adjustment, and the object of the invention is to provide means whereby, when the screw is adjusted, it or the part or element acted upon by it will reliably retain 15 that adjustment without requiring the employment of any additional agency such as a jam nut. In other words, the adjustment when made will remain permanent until intentionally altered by means of a tool and a 20 considerable amount of tool-actuating force.

The motors of many automobiles such as the Buick, Marion, Franklin and Dort, employ valves the stems of which are engaged by levers usually referred to as rocker arms, 25 said levers being actuated by reciprocating rods. In order to ensure proper seating of the valves it is essential that provision be made for adjusting the valve-actuating mechanism. While the accompanying drawings 30 illustrate the invention as applied to or used in connection with a lever or rocker arm such as just referred to, it is to be understood that I do not limit myself to such use, as the invention is practically applicable 35 to a wide variety of mechanisms which employ adjusting screws.

Of the drawings:

Figure 1 is a side elevation of the lever or rocker arm and its adjusting member, and 40 portions of other parts.

Figure 2 is a plan view.

Figure 3 represents a section, enlarged, on line 3—3 of Figure 1.

Figure 4 represents a section at a right 45 angle to Figure 3, and omitting the screw member.

Figures 5 and 6 are views similar to Figures 3 and 4 but illustrating the tongue of the rocker arm as smooth-bored instead of 50 threaded.

Similar reference characters indicate similar parts in all of the views.

The element of the combination which 55 couples the rocker arm to the screw comprises a block or blank which is slotted or

recessed in one side as at 14 to form a lower part 12 and an upper part 13 connected by a neck 15. The parts 12, 13, are provided with threaded holes which are not quite in alinement, as best illustrated by Figures 3 60 and 5. So far as the threaded holes are concerned, the parts 12, 13, are relatively offset laterally so that the threads of said holes are out of uniform continuity in order that said threaded holes will automatically grip 65 the threads of the male screw member presently described. This result may be attained by forming a hole through the parts 12, 13, of the blank while said parts are held distorted, then tapping said hole while said 70 parts are held distorted, and then returning said parts, or permitting them to return, to substantially their original relative positions.

The screw 16, illustrated as having a top 75 recess 17 to be engaged by a suitable adjusting tool, has a foot 18 which fits a socket 19 in the upper end of a rod 20 which, in practice, is usually actuated by a cam. The rocker arm 21, pivotally supported at 22 as 80 usual, has at one end a projection 23 which, for convenience, is referred to as the tongue. Said tongue 23 extends into the recess 14 and has a hole through which the screw 16 passes. Said hole in the tongue may be 85 threaded to fit the thread of the screw as illustrated by Figures 3 and 4, or may be a smooth bored hole large enough to clear the screw threads as illustrated by Figures 4 and 5. The other end of the rocker arm has the 90 usual tappet 24 bearing on the upper end of the stem 25 of a valve. It will be readily understood that this specific structure illustrated and described is intended for use in mechanisms wherein the rod 25 has a constant tendency to rise, as by means of a 95 spring not necessary to illustrate.

Referring to Figures 3 and 5, it will be seen that the threaded holes in the parts or members 12, 13, are not in alinement, the 100 amount of offsetting being somewhat exaggerated in said figures in the interest of clearness of illustration. The result is that the internal threads of the portion 12 grip both the upper and lower inclined surfaces 105 of the threads of the male member 16 on one side, while the internal threads of the portion 13 grip both the upper and lower inclined surfaces of the threads of the male member on the opposite side. In other 110

words, there is an inward pressure of the female member against opposite sides of the male member and at different distances longitudinally of the latter.

5 The pressure or gripping action is such that the screw 16 can not accidentally rotate. When adjustment is to be made, considerable force must be employed, as by a screw driver engaged with the recess 17, 10 or by a wrench if the top of the screw is suitably formed with flat side faces. The screw 16 and the rocker arm 21, through which motion is transmitted from the rod 20 to the member 23, will remain in fixed 15 relative positions except when manually and forcibly adjusted.

The essential feature of the invention comprises three members one of which is the recessed member having threaded apertures in its portions 12, 13, the threads of 20 said apertures being out of uniform or direct continuity, another being the member 23 in said recess, and the third being the male threaded member 16 engaged with 25 said threaded apertures and automatically or self gripped thereby. Therefore it will readily be understood that for some purposes the member 23 might be stationary, the recessed member mounted thereon, and 30 the screw 16 then employed to adjust something engaged thereby.

Having now described my invention, I claim:—

1. An automatically-gripping adjustable coupling comprising a recessed member provided with threaded apertures out of alignment, an intermediate member in said recess and forming a part of the coupling, and a male threaded member engaged with said threaded apertures. 35

2. Mechanism of the character described, comprising a recessed member provided with threaded apertures out of alignment, a male threaded member engaged with said threaded apertures, and a movable member 40 having a tongue entering the recess of the first-mentioned member, said tongue having an aperture for the passage of said male member. 45

3. The combination with a member having internal threads some of which are displaced relatively to others, of a male threaded member engaged therewith, and a lever positively engaged with the internally threaded member. 50

4. The combination with a rocker arm having a tongue at one end, of a recessed member mounted on said tongue and having upper and lower threaded apertures out of alignment, and a screw engaged with said threaded apertures and passing through the tongue of the rocker arm. 55

In testimony whereof I have affixed my signature.

JULIAN K. BRYANT.
